LIGHTER FOR SMOKERS

Guy Neyret, Francheville, France, assignor to Etablissements Genoud & Cie, Venissieux, Rhone, France

Filed Nov. 30, 1973, Ser. No. 420,673

Claims priority, application France June 13, 1973

Term of patent 14 years

Int. Cl. D27—05

U.S. Cl. D27—42

FIG. 1

FIG. 2

FIG. 4

FIG. 3

FIG. 1 is a perspective view of a lighter for smokers showing my invention;

FIG. 2 is an elevational view thereof from the end which is invisible in FIG. 1;

FIG. 3 is a broad side elevational view thereof showing the side which is invisible in FIG. 1; and

FIG. 4 is a bottom plan view thereof.

The lighter is shaded to indicate contrast.

I claim:

The ornamental design for a lighter for smokers, as shown and described.
